UNITED STATES PATENT OFFICE.

THOMAS E. BARNUM, OF WAUWATOSA, AND ERWIN R. STOEKLE, OF MILWAUKEE, WISCONSIN, ASSIGNORS TO THE CUTLER-HAMMER MFG. CO., OF MILWAUKEE, WISCONSIN, A CORPORATION OF WISCONSIN.

PROTECTIVE DEVICE FOR ELECTRIC CIRCUITS.

Application filed February 25, 1922. Serial No. 539,117.

To all whom it may concern:

Be it known that we, THOMAS E. BARNUM and ERWIN R. STOEKLE, citizens of the United States, residing, respectively, at 5 Wauwatosa and Milwaukee, in the county of Milwaukee and State of Wisconsin, have invented new and useful Improvements in Protective Devices for Electric Circuits, of which the following is a full, clear, 10 concise, and exact description, reference being had to the accompanying drawing, forming a part of this specification:

This invention relates to protective devices for electric circuits, and more particularly to protective devices involving a vaporizable electrical conductor which is liquid at working temperatures.

In a patent of Erwin R. Stoeke, No. 1,556,134, dated October 6, 1925, is disclosed 20 and claimed such a type of protective device having certain features in common with that herein contemplated.

In numerous installations the use of a protective device of the character aforesaid, 25 adapted to provide both overload and underload protection, would be exceedingly desirable and the present invention has among its objects that of providing such a device.

Another object is that of providing a unitary protective device having the characteristics last mentioned.

Another object is that of providing such a device having certain elements thereof 35 so designed, constructed and arranged as to afford an exceedingly simple, compact and convenient structure.

Another object is that of providing for 40 housing of such protective devices in an improved manner.

Other objects and advantages will hereinafter appear.

In the accompanying drawing,

Fig. 1 is a vertical sectional view illustrating a preferred embodiment of the invention, certain parts being shown in front elevation and certain circuit connections being illustrated diagrammatically; while,

Fig. 2 is a similar sectional view illustrating a modified construction wherein certain elements more nearly resemble the corresponding parts of prior devices.

Referring to Fig. 1 of the drawing, the

same illustrates a combined overload and underload protective unit comprising a pair 55 of electrodes arranged in the circuit to be protected and adapted, under normal conditions to be connected by a conductor which is liquid at working temperatures, an electric heating element, to be energized from the circuit in accordance with an electrical 60 condition of which control of the protected circuit is desired, is adapted under given conditions of overload to effect vaporization of said liquid conductor for sudden interruption of the protected circuit. Moreover one of said electrodes is capable of being moved out of engagement with the liquid conductor and is biased to so move, while an underload device serves, when energized 70 above a given critical value, to prevent such movement.

More specifically the device as illustrated in Fig. 1 includes a support 5, of molded insulating material or the like preferably cylindrical in shape, having a multi-diameter bore 6 to contain a liquid conductor 7, said bore having upwardly facing annular shoulders 8 and 9 and the lower portion thereof being materially constricted at 10 substantially as shown. A cover plate 11 of like material and a bottom plate 12 preferably of asbestos lumber or the like are secured to the support 5 preferably by means of the bolts 13 as shown, said cover plate having 75 a passage 14 and said bottom plate having a shouldered cylindrical recess 15, both in substantial alinement with the bore 6 of said support.

A flat electrode 16, preferably circular in 80 shape, is clamped between the bottom plate 12 and the support 5 in a manner to close the bore 6 in the latter, whereas, a similarly shaped shield 17 of mica or other insulating material is likewise clamped against the 85 bottom of said electrode 16. In practice said electrode and said shield are preferably carried upon the aforementioned annular shoulder of the bottom plate 12.

A flat electrical heating element 18, which 90 in practice may be either spiral, zig zag or of other desired formation, is mounted below the shield 17 and within the recess 15 of the bottom plate, said heating element having a terminal carried without said recess through 105 a suitable opening and preferably attached.

to one of the bolts 13 as illustrated. The opposite terminal of said heating device may be led through a suitable opening in the shield 17 and spot welded, soldered or otherwise permanently electrically connected with the electrode 16 as shown, such construction being preferable in installations wherein said heating element and said electrode are to be connected in series. Where 10 said elements are to be connected in separate circuits, said second terminal of the heating element is preferably led without the recess 15 and connected to the other of the bolts 13 in the manner just described.

15 A second electrode 19 is adapted to extend through the aforescribed opening in the cover plate 11 and to project within the enlarged portion of the bore 6 of support 5, being further adapted to reciprocate within 20 said bore. The lower portion of said electrode is preferably enlarged, substantially as illustrated, and provided with a downwardly facing flat surface to co-operate with the upwardly facing shoulder 9 of said bore 25 in the manner of a valve and its seat for closure of said bore when said electrode is in its extreme downward position.

The lower enlarged portion of said electrode is further provided with a restricted 30 passage 20 serving to connect the constricted portion of the bore 6 with the region above the enlarged head of said electrode. Said constricted portion 10 of the bore 6 is filled 35 with a liquid conductor 7 which in practice may comprise metallic mercury, and which serves under normal conditions to connect electrically the aforescribed electrodes. The enlarged portions of the bore 6 may in 40 practice also contain a limited quantity of the conductive fluid which, however, should under no conditions be permitted to attain the level of the upper end of the passage 20.

45 The electrode 19 is adapted to extend a considerable distance above the cover plate 11 substantially as illustrated.

An angular magnetic frame 21 preferably 50 of laminated construction is permanently mounted above the support 5 and is provided with a magnetic plug 22 extending in a direction substantially parallel with the electrode 19. An electromagnetic coil 24 is mounted upon said plug as shown.

A magnetic lever 26 also preferably comprising laminations is pivotally mounted 55 near the upper end of the vertically extending limb of the frame 21, said lever being arranged to project substantially horizontally forward from the frame 21 and being adapted to act as an armature for attraction 60 toward the adjacent end of the plug 22. The upper end of the electrode 19 is connected with an intermediate portion of said lever 26 by means of an insulating link 27 and a pin 28 which is carried by said lever in a 65 relation to project laterally beyond the coil

24. A spring 29 serves to bias the lever 26 and its connected parts to move upwardly, whereas the downward magnetic pull upon the lever 26 predominates the force of said spring for all values of energization of coil 70 24 above a given or predetermined value.

The coil 24 is connected in the circuit in accordance with an electrical condition of which underload protection is desired and 75 where said circuit is the same as that controlled by the overload elements aforescribed one coil terminal is preferably connected with an upper portion of the electrode 19 by means of a flexible lead 30 as shown.

In practice the support 5 is preferably secured upon a suitable panel 31 by means of an angle bracket 32 to which said support may be clamped by means of one of the bolts 13 as illustrated. Furthermore the magnetic frame 21 is preferably provided with outwardly bent feet such as that illustrated 85 at 33 for clamping said frame and its attached parts to the same panel above the location of the support 5.

Said panel is preferably hinged upon a suitable switch box 34 to constitute the door or cover therefor and is provided with a suitable slot 35 through which the end of lever 26 is adapted to extend, said lever being preferably provided on the outside of 90 said panel with a suitable insulating handle 36.

By the foregoing construction and arrangement the switch parts are enclosed 100 within the box when the cover is closed and moreover upon opening of said cover all of said parts are swung outwardly into a position affording ready and complete accessibility for calibration or inspection.

The operation of the device may be described as follows, the circuit connections being assumed to be those illustrated in Fig. 1, that is to say, the heater, the overload circuit interrupting elements and the underload coil being all connected in series in the circuit to be protected. Under normal conditions the pull of the underload coil plus the effective weight of the parts subjected to such pull is sufficient to predominate the force of the spring 29 for maintaining the electrode 19 in its extreme downward position and in contact with the liquid conductor for maintaining circuit. However, upon failure or given reduction of the energization of said underload coil the force of the spring predominates and lifts the electrode 19 out of contact with the liquid conductor thereby interrupting the circuit.

Also under overload conditions of given magnitude and duration the heater coil becomes energized to a degree sufficient to effect vaporization of the liquid conductor located within the constriction 10, subject 125 however, to an inverse time element due to 130

heat absorption by the support 5 and bottom plate 12. Thereupon the portion of the liquid conductor located above the region of vaporization is expelled upwardly 5 through the passage 20 and such expulsion serves to effect sudden interruption of the controlled circuit. Such action obviously terminates the energization of the underload coil 24 whereupon again the spring 29 acts 10 to lift the electrode 19 to its extreme upper position and out of contact with the liquid conductor which latter is now free to return within the constricted passage 20 and to remain in its normal position.

15 Obviously following interruption of circuit under either of the conditions aforescribed the circuit may be re-established by a downward pull upon the lever 26 such as to effect re-engagement of the electrode 19 20 with the liquid conductor, and the circuit as thus completed will be maintained so long as normal conditions prevail due to re-energization of the underload coil 24.

Referring now to Fig. 2 of the drawing, 25 the same illustrates a modified form of apparatus including parts possessing more marked structural analogy to those of the patent of Erwin R. Stoekle aforesigned.

In this instance an insulating base 5^a 30 serves as a support for the parts associated therewith, said base being provided with a multi-diameter bore having an intermediate constricted portion 10^a and terminally located enlarged recesses 40 and 41. A helical heating coil 18^a is arranged within the recess 40 being retained by a body 42 of cement or the like. A tube 43 of glass or the like is arranged within said heating coil and adapted to terminate below the constriction 35 10^a aforescribed, said tube also being retained by the cement or the like. The bore within the support 5^a is provided immediately above the constriction 10^a with a flat annular shoulder 9^a constituting in effect a 40 valve seat, while a valve shaped electrode 19^a is adapted to co-operate with said seat for closing said passage. The enlarged head of 45 said valve is also provided with a diagonally arranged passage 20 extending upwardly 50 from the constricted passage 10^a to the region above said valve head, all in the manner described in connection with Fig. 1.

A suitable electrode 16^a is secured within the lower end of the tube 43 preferably substantially as shown, and terminates within the heating coil 18^a. In practice the space within the tube 43 and also within the constricted portion of the bore 6^a is filled with 55 a conductive medium 7 which is liquid at working temperatures, such liquid being adapted normally to rise within the upper recess 41 of the support 5^a to a level at all times materially lower than the upper terminal of the passage 20.

60 In this construction the magnetic frame 65

21^a is secured to the upper portion of the support 5^a by bolts 44 or the like substantially as shown, a washer 45 of leather or the like being interposed to provide a liquid tight fit. Said frame 21^a is provided with 70 vertically aligned and relatively enlarged openings to receive a magnetic tube 22^a and also an insulating sleeve 23 said tube being of such length as to extend a considerable distance above the frame as shown. An 75 electromagnetic coil 24^a having the usual end washers is mounted upon the sleeve 23 within the frame. A spacing member 25 preferably of insulating material having a longitudinal bore 46 is arranged within the 80 tube 22^a the latter being mounted so as to be attracted downwardly under the influence of the flux due to energization of said coil.

85 The upper end of the electrode 19^a is reduced and is adapted to extend longitudinally through and beyond said bore 46 of the member 25, being preferably secured to the latter and to the tube 22^a by means of a pin 47 as illustrated. A washer 48 is located about the magnetic tube 22^a above the frame whereas another washer 49 and a terminal device 50 are clamped upon the upper end of the electrode 19^a by means of a nut 51, while a suitable knob or button 53 is also 90 threaded upon the projecting end of said electrode.

95 A helical spring 54 is arranged between the washers aforescribed and serves to bias the aforescribed reciprocable parts 100 upwardly, said spring being of reduced power such as to be predominated by the electromagnetic pull during energization of the coil 24^a above a predetermined value, whereby the valve is maintained seated against 105 the action of said spring. However, if at any time the energization of the coil falls below such predetermined value the force of the spring predominates for lifting its associated parts including the electrode 19^a 110 which is thus elevated out of engagement with the liquid conductor, thereby interrupting the controlled circuit in response to the aforesigned reduction in energization of the coil 24.

115 As illustrated, the heating coil and the underload coil are connected in series in the circuit which is to be protected, the liquid conductor and its associated electrodes, however, being connected in a different circuit, in this instance the energizing circuit of the switch which controls the protected circuit.

120 The operation of the complete device is in all material respects similar to that of 125 the aforescribed construction.

As is apparent from the relative size of corresponding parts of the two devices aforescribed, the type employing the flat heating element intimately associated with a cor-

respondingly shaped electrode is characterized by a somewhat augmented sensitiveness of operation providing an exceedingly sensitive control where the values of electrical energy to be handled are not excessive and permitting the use of parts of reduced size and complexity of construction.

What we claim as new and desire to secure by Letters Patent is:

- 10 1. A protective device for electric circuits comprising relatively movable electrodes, a conductor for connecting the same which is liquid at working temperatures, means subjecting said liquid conductor to a heating effect for interruption of circuit between said electrodes under given conditions and means to automatically effect relative movement of said electrodes for interrupting circuit therebetween under other conditions.
- 15 2. A protective device for electric circuits comprising a conductor which is liquid at working temperatures, relatively movable electrodes to be electrically connected by said conductor, means to effect relative movement of said electrodes for interruption of circuit therebetween and means to effect interruption of circuit between said electrodes by heating of said liquid conductor and to further effect operation of said means for relative movement of said electrodes to prevent re-establishment of circuit therebetween upon restoration of said liquid conductor to its normal state.
- 20 3. A protective device for electric circuits, comprising a conductor which is liquid at working temperatures, relatively movable electrodes to be connected thereby, said electrodes requiring restraint in a given relation for connection thereof by said conductor and means to so restrain said electrodes subject to release upon interruption of the continuity of said liquid conductor.
- 25 4. A protective device for electric circuits, comprising a conductor which is liquid at working temperatures, relatively movable electrodes to be connected thereby, said electrodes requiring restraint in a given relation for connection thereof by said conductor, means to so restrain said electrodes subject to release upon interruption of the circuit therethrough, and means subjecting said liquid conductor to thermal influence to interrupt the circuit between said electrodes automatically under given conditions.
- 30 5. In a protective device for electric circuits, the combination with a conductor which is liquid at working temperatures, electrodes providing circuit connections for said conductor, and means to vaporize and expel liquid of said conductor from between said electrodes for interrupting circuit, certain of said electrodes being movable to provide for return of the expelled fluid and means for so moving said certain of said electrodes and at the same time withdraw-

ing the same out of contact with the fluid to maintain the circuit interrupted pending voluntary reclosure.

6. In a protective device for electric circuits, the combination with a conductor which is liquid at working temperatures, electrodes providing circuit connections for said conductor, and overload means to vaporize liquid of said conductor for interrupting circuit between said electrodes, one of said electrodes being movable to provide for restoration of continuity of said conductor, means tending to effect such movement of said electrode and normally preponderant electro-responsive means opposing such movement of said electrode.

7. In a protective device for electric circuits, the combination with a conductor which is liquid at working temperatures, electrodes providing circuit connections for said conductor, and overload means to vaporize liquid of said conductor for interrupting circuit between said electrodes, one of said electrodes being movable out of contact with said conductor, means tending to so move said electrode and means for holding said electrode against such movement under all conditions of energization, above a given value, of the circuit to be protected, subject to release and consequent movement of said electrode under lesser degrees of energization of said circuit.

8. A protective device for electric circuits, comprising electro-responsive means for interrupting circuit under given conditions of overload and underload selectively, said means including a vaporable conductor which is liquid at working temperatures.

9. A protective device for electric circuits comprising relatively movable electrodes, a conductor which is liquid at working temperatures connecting said electrodes, means for displacing a portion of said conductor to break the circuit under predetermined overload conditions, and co-operating electro-responsive means adapted to break said circuit under predetermined underload conditions.

10. A protective device for electric circuits comprising relatively movable electrodes, a conductor which is liquid at working temperatures interposed between said electrodes, manually operable means for moving said electrodes to circuit making or circuit breaking position with respect to said liquid conductor, said electrodes being biased to circuit breaking position, electro-responsive means for maintaining said electrodes in circuit making position subject to release upon given underload conditions, and thermo-electric means to displace a portion of said liquid conductor to break circuit upon given overload conditions.

11. An electro-responsive switch to control either its own energizing circuit or an asso-

100

105

110

115

120

125

130

- ciated circuit, comprising a conductor which is liquid at working temperatures, insulating means providing a column of said conductor, electrodes to be in contact with terminal portions of said column respectively, thermo-electric means to effect vaporization and consequent displacement of liquid of said conductor under given conditions of overload for interrupting circuit between said electrodes, one of said electrodes being movable out of contact with said liquid conductor, a spring tending so to move said electrode, and an underload coil adapted to prevent such movement of said electrode under normal conditions.
12. A circuit interrupter comprising a tubular base, spaced electrodes and a connecting liquid conductor carried by said base, one of said electrodes being movable with respect to said base and being provided with an internal passage and an associated valve to co-operate with a seat provided on said base, a heating element to vaporize and displace liquid of said conductor between said electrodes for causing an upward flow of fluid of said conductor through said passage for interruption of circuit between said electrodes, said passage being arranged to prevent return of liquid therethrough, said valve being voluntarily operable to permit return of the displaced fluid and said latter electrode being movable out of engagement with said liquid conductor, electro-magnetic means to resist such movement of said electrode and means to predominate said latter means under given electrical conditions for so moving said electrode to interrupt circuit.
13. In a circuit interrupter, the combination with a tubular base, spaced electrodes and a connecting liquid conductor carried within said base, thermo-electric overload means to act upon said conductor for interrupting circuit between said electrodes, means including an electro-magnetic frame and an operating lever, to act upon one of said electrodes for interrupting such circuit under given underload conditions, a switch box to contain said parts, said box having a hinged cover panel and means for securing said base and said frame to the inner side of said panel to swing therewith out of said box, said panel having an opening permitting said lever to protrude from said box.

In witness whereof, we have hereunto subscribed our names.

THOMAS E. BARNUM.
ERWIN R. STOEKLE.
